Primary Examiner — Patricia A Palasik(74) *Attorney, Agent, or Firm* — Cathy J. Futrowsky,
Evans & Dixon, L.L.C.(57) **CLAIM**

The ornamental design for an underwater robot, as shown and described.

DESCRIPTION

FIG. 1 is a front view of an underwater robot showing my new design;

FIG. 2 is a rear view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

The broken lines shown in the figures depict portions of the underwater robot that form no part of the claimed design.

1 Claim, 5 Drawing Sheets(56)
